WALTER COX, OF PHILADELPHIA, PENNSYLVANIA, ASSIGNOR TO PENNSYLVANIA WIRE GLASS COMPANY, OF PHILADELPHIA, PENNSYLVANIA, A CORPORATION OF NEW JERSEY.

CRATE FOR SHEET-GLASS.

1,175,898.

Specification of Letters Patent. Patented Mar. 14, 1916.

Application filed July 17, 1914. Serial No. 851,430.

To all whom it may concern:

Be it known that I, WALTER Cox, a citizen of the United States, and a resident of Philadelphia, in the county of Philadelphia and State of Pennsylvania, have invented a certain new and useful Crate for Sheet-Glass, of which the following is a specification.

The principal object of the present invention is to provide a crate for sheet glass which is rigid and protects the glass, which remains in good condition during and after transportation and shipment and which for its construction requires comparatively little or light pieces of lumber.

The invention consists in the combination and arrangement of parts producing a crate which is a new article of manufacture and is possessed of advantages, all of which will be hereinafter described and claimed, but first reference will be made to the accompanying drawings, in which—

Figure 1, is a side view partly in elevation and partly in section of a crate embodying features of the invention. Fig. 2, is an end view of the crate, and Fig. 3, is a section taken on the line 3—3 of Fig. 1.

The sides of the crate are both alike and one of them will be described. 30 1 and 2 are top and bottom rails. Between these rails there is a lattice consisting of center pieces 3 and generally wedge-shaped end pieces 4, disposed normally or at right angles to the top and bottom rails. 35 The lattice also comprises two series of preferably upwardly divergent slats 5, extending between the top and bottom rails 1 and 2 and disposed respectively between the center and end pieces. These slats 5 are 40 shown as alined with the inclined faces of the end pieces 4. The lattice also comprises two cross bars 6 meeting at an obtuse angle at the center and extending to the pieces 4. The bottom 7 is arranged between the parts 45 3, 5, and 4. The ends 8 are arranged between the parts 4. The top 9 is applied on top of the ends. The various parts are secured together as by nails or like fastenings which are indicated, for example, at 10 50 on the drawings. Cleats 11 are applied to

the ends of the crate and connect the top and bottom rails respectively and bind in the ends and also the bottom 7.

The lattice can be constructed by nailing its various parts together as shown and can 55 then be applied by nailing it to the bottom and ends of the box, whereupon the cleats 11 can be applied, thus completing the box structure. The described structure by reason of the disposition of its parts, including 60 the lattice sides, is rigid and strong. The lattices may be said to be top and bottom cords connected by struts and tie-pieces and they are therefore capable of carrying great weight even though supported unevenly or 65 at intervals and they are capable of resisting thrust applied at the ends, so that the crate resists the strain put upon it as when it is carried or pushed, which are things to which it is subjected in transportation and 70 handling. The lattice structure permits of the use of comparatively little and light lumber in proportion to its strength, because the material is so distributed as to be in the places where it is needed to carry the 75 loads or resist the strains or stresses incident to the shipment and handling of the crate. For the reason stated the crate is not only well adapted to protect sheet glass in transportation, but the crate remains intact and 80 can be used for reloading and if necessary storing the goods.

What I claim is:

1. A crate for sheet glass having in combination a top, a bottom and ends, and sides 85 each consisting of top and bottom rails having between them a lattice of perpendicularly disposed center and end pieces and two divergent series of slats disposed at the opposite sides of the center pieces, and two 90 cross bars meeting at an obtuse angle in the center.

2. A crate for sheet glass having in combination a top, a bottom and ends, sides 95 each consisting of top and bottom rails having between them a lattice of perpendicularly disposed center and end pieces and two divergent series of slats disposed at the opposite sides of the center pieces and two 100 cross bars meeting at an obtuse angle in the

center, and cleats at the ends joining the top and bottom rails respectively.

3. A crate for sheet glass having in combination a top, a bottom and ends, and similar sides each consisting of top and bottom rails having between them a lattice of two divergent series of slats, and two cross bars meeting at an obtuse angle in the center.

In testimony whereof I have hereunto signed by name in the presence of witnesses. 10

WALTER COX.
